KNITTING MACHINE

Leah H. Boxer, San Francisco, Calif., assignor of
one-third to J. E. Trabucco, San Mateo, Calif.

Application March 20, 1951, Serial No. 216,579

9 Claims. (Cl. 66—4)

1

This invention relates to improvements in knitting machines.

The present invention provides an improved hand knitting machine which is capable of being easily operated to produce knitted articles from yarn or the like. The knitting machine embodying the principles of my invention comprises a plurality of laterally spaced work holding members arranged in cooperative relation with a plurality of loop forming pins which are mounted for forward simultaneous adjustment to a strand engaging position extending between the work holding members and then to rearward loop forming positions. The work holding members are provided with hooked ends which hold the strand as the loop forming pins are adjusted rearwardly to form a row of loops. Pivoted latches mounted on the work holding members are swung to positions closing the hooked ends of the said members when the work is shifted rearwardly to effect the engagement and tying of the loops by the preceding row of knitted loops. The work holding members are carried on a rigid bar which is adapted to be manipulated to disengage the tied loops from the loop forming pins. The loop forming pins are simultaneously adjusted to their forward strand engaging positions by a spring loaded pin actuator, and a cam bar arranged for successive engagement with the said pins is used to shift them rearwardly. The relative positions of the adjacent ends of the work holding members and the loop forming pins may be changed to permit a coarser or finer knit to be produced.

The principal object of my invention is to provide a novel hand knitting machine of the kind characterized which is designed to facilitate greater speed and accuracy in the knitting of fabrics.

In the accompanying drawings:

Fig. 1 is a perspective view of a knitting machine embodying my invention;

Fig. 2 is an end view, on an enlarged scale, of the machine;

Fig. 3 is a side elevation of a conventional tool which may sometimes be used in adjusting the position of a strand during a knitting operation;

Fig. 4 is a perspective view of a cam bar used in shifting the loop forming members rearwardly;

Fig. 5 is a top plan view of the knitting machine;

Fig. 6 is an enlarged sectional view taken on the line 6—6 of Fig. 5;

Fig. 7 is an enlarged diagrammatic detailed view showing the relative positions of the work holding members and the loop forming pins prior to the commencement of the knitting operation;

Fig. 8 is a similar view showing the pins in for-

2

wardly adjusted positions with a strand arranged in engagement therewith;

Fig. 9 is a similar view showing the pins after they have been shifted rearwardly to form a row of loops; and

Fig. 10 is a similar view showing the loops tied by a previously knit row of loops which were shifted rearwardly from the work holding members.

Referring to the drawings the numeral 1 designates an elongated frame which is preferably somewhat U-shaped in cross section. Secured to and depending from the frame are C-clamps 1a for securing the machine to a table A or other supporting structure. Affixed to the ends of the frame is a longitudinally disposed U-shaped channeled pin guide 2 having a plurality of uniformly spaced guide slots 3 extending transversely in parallel relation with respect to each other. The upwardly disposed sides or legs of the channeled pin guide 2 are also provided with a plurality of pairs of forwardly and rearwardly disposed guide holes 4, the said holes of each pair being arranged in a vertical plane extending through an associated guide slot 3.

Mounted for rearward and forward adjustment in the guide slots 3 and guide holes 4 are a plurality of uniformly spaced parallel loop forming pins 5 which are each provided with a rearwardly extending horizontal portion 5a, a U-shaped portion 5b which projects through an associated guide slot 3, a forwardly extending horizontal portion 5c and an upstanding vertical portion 5d (Fig. 6). It will be noted that the U-shaped portion 5b and the upwardly disposed portion 5d of each pin are in a common vertical plane, also that the said upright portion 5d is maintained in an upwardly projecting vertical position by reason of the U-shaped portion 5b engaging with its associated guide slot 3. The pins 5 are all the same shape and length.

Mounted for forward and rearward movement inside the frame 1 is a longitudinally extending L-shaped pin actuator 6 which is arranged to engage with the rear ends of all of the loop forming pins 5. The pin actuator 6 rests on the bottom side of the frame 1, and a centrally disposed finger piece 7 secured to the actuator and extending through a hole in the rear side of the said frame provides means for pushing the actuator

forwardly to simultaneously adjust all of the pins 5 to their forward strand engaging positions. A tensioned leaf spring 1a interposed between the pin actuator 6 and the forward portion of the frame serves to return the pin actuator to its rearward position as shown in Fig. 6. The loop

forming pins 5 when in their forwardly projected positions are positioned with their U-shaped portions 5b abutting the forward ends of the slots 3 and their upstanding portions 5d extending in longitudinal alignment well in front of the frame 1.

An elongated cam bar 8 (Fig. 4) having longitudinal parallel edges and having both of its ends formed with inclined metal faced cam surfaces as at 8a, is used to successively actuate the loop forming pins 5 rearwardly to form loops in an engaged strand, as will be presently described. The cam bar 8 with its inclined cam surfaces facing rearwardly may be projected inwardly from either end of the machine. When using the cam bar either pointed end thereof is first inserted between the forward side of the channeled pin guide member 2 and the forward leg of the U-shaped portion 5b of an end pin 5. As the cam bar is manually projected inwardly from the left or from the right the advancing cam surface 8a successively engages with the U-shaped portions 5b of the pins 5, and thereupon shifts the latter rearwardly.

Secured to the ends of the frame 1 are metal members 9 which have outwardly projecting screws 10 secured rigidly thereto. Adjustably supported on the metal members 9 by means of the screws 10 are end plates 11 which are slotted as at 12. The screws 10 extend outwardly through the slots 12, and wing nuts 13 threaded on the screws serve to securely hold the end plates 11 in fixed positions with respect to the frame. The slots 12 of the end plates are arranged to permit the backward and forward adjustment of the said end plates. Suitable graduation marks positioned alongside one of the slots 12 of each end plate 11 provide guide means to be used in association with an associated screw 10 for the corresponding forward or rearward adjustment of the end plates. The end plates 11 are correspondingly grooved as at 11a and 11b. The rear grooves 11a provide openings permitting the insertion of the cam bar 8, and the forward grooves 11b provide openings and seats for the movement and support of an elongated bar 14.

The elongated bar 14 carries a plurality of parallel rearwardly extending work holding members or pins 15 which are normally arranged in a substantially horizontal common plane, the said members being uniformly spaced in accordance with the spacing of the pins 5. The work holding members 15 are so arranged and positioned on the bar 14 that they are adapted to project between and in spaced relation with respect to the upstanding portions 5d of pins 5 when the latter are in their forwardly adjusted positions. The work holding members 15 are of uniform length and their rear ends are provided with upstanding hooks which are adapted to be closed by pivoted latches 16. The latches 16 are pivotally mounted on the members 15, and when in open positions they are adapted to extend rearwardly from their pivots to positions alongside their respective members 15, thereby permitting the knitted work to be pulled forwardly past them to a position engaging with the bar 14. The latches 16 are adapted to be swung rearwardly to closed positions with respect to the hooked ends of the members 15 when the work is manually shifted rearwardly to transfer the last knitted row of loops from the said members to the row of loops then being held by the pins 5, as will be later described. Upon the closing of the hooked ends of

the work holding members 15 with the rearward pivotal movement of the latches 16, the previously knit loops of the work may be pulled rearwardly over the said hooked ends of the members 15 to engaging positions with the loops then held by the pins 5.

Secured to the bar 14 near its opposite ends are depending flanges 17 which engage with the inner opposed faces of the end plates 11, thereby normally preventing the lateral shifting of the said bar to positions which would change the relative positions of the work holding members 15 with respect to the loop forming pins 5.

A cover plate 18 is preferably secured to the frame to enclose the opening located above the pin actuator 6.

The bar 14 is adapted to be manually shifted or turned to lift the hooked ends of the work holding members 15 upwardly to free the loops then held by the pins 5 from the latter.

A suitable tool T having a shape such as that illustrated in Fig. 3 may be used during a knitting operation to rearrange portions of the knitted material in accordance with predetermined designs.

A scale 19 having slidable markers 20 thereon is preferably provided on the upper surface of the bar 14 to facilitate the knitting of fabrics having various designs.

Preferably, at the commencement of a knitting operation an elongated cloth strip is first threaded over the work holding members 15 and pulled forwardly against the bar 14, after which a detachable thread is secured by knitting to the cloth strip. The purpose of the cloth strip is to provide a convenient device for manually shifting the knitted work to which it becomes attached, backwardly and forwardly during the knitting operation as will be presently described. The work when completed may be easily detached from the cloth strip by pulling the thread outwardly. After the removal of the cam bar 8 the loop forming pins 5 are shifted to their forward strand engaging positions by pressing the enlarged end of the finger piece 7 forwardly toward the frame 1. When thus shifted forwardly to the extent permitted by the ends of the guide slots 3, the upwardly disposed portions 5d of the loop forming pins will be positioned forwardly of the hooked rear ends of the work holding members 15. The upwardly hooked ends of the members 15 extend upwardly between and above the forward horizontal portions 5c of the pins. The latch members 16 should be swung forwardly to positions resting on the horizontal portions of the work holding members 15. As illustrated in Figs. 7 to 10, with the various operating parts of the machine positioned as just described, a strand S of yarn or the like is extended rearwardly and to the left in engagement with a certain pin 5 and then transversely along the rear sides of those pins which are to be utilized in the knitting operation, depending upon how wide the knitted fabric is to be. (Fig. 7.) The strand is extended forwardly from the selected left hand pin 5 toward the bar 14; there it is loosely held so it may freely slip rearwardly when the loops are subsequently formed. The cam bar 8 after being inserted between the U-shaped pin guide 2 and the forward leg of the U-shaped portion 5b of that particular pin 5 which is positioned at the right end of the machine, is pushed to the left, thereby causing the loop forming pins 5 to be successively shifted rearwardly. Those pins which are positioned in engagement with the strand S upon

being shifted rearwardly form a series of loops, as shown in Fig. 9. The work is then shifted rearwardly on the work holding members 15, thereby passing under the slightly upturned free ends of the latches 16 and thereupon causing the said latches to swing rearwardly to positions in which their said free ends engage with and close the hooked ends of said members. As the work is continued to be shifted rearwardly the last 10 knit row of loops thereof (or the row of loops formed by the thread) are transferred from the work holding members 15 to the loops then held by the loop forming pins 5. These transferred loops extend over and around the thusly held loops (Fig. 10), and thereafter the said transferred loops operate to tie the held loops, as in the ordinary knitting operation. The bar 14 is then partially turned or shifted to lift the hooked end of the work holding members 15 upwardly, thereby disengaging the tied loops from the pins 5. When this latter operation is carried out, the work is preferably pulled downwardly by the operator's hand, after which the said work is pulled 20 forwardly toward the bar 14, thereby opening the latches, preparatory to the next operation.

Having described my invention, what I claim is:

1. In a knitting machine, an elongated frame having a bar supporting means at its forward side, an elongated adjustable bar mounted on the supporting means of the frame, a plurality of rearwardly extending uniformly spaced work holding members carried by the bar and normally arranged in substantially horizontal positions, the said work holding members having upturned hooked rear ends and pivoted latches arranged to swing between a position extending forwardly alongside the members and a position extending rearwardly in engagement with the said hooked ends, a plurality of upstanding uniformly spaced pins mounted for forward adjustment to forward positions extending between the hooked ends of the work holding members and to positions rearwardly of the said hooked ends of the work holding members, means for shifting the pins forwardly and means for adjusting the pins rearwardly.

2. In a knitting machine, an elongated frame having a bar supporting means at its forward side and a pin supporting guide, an elongated bar mounted for rotative adjustment on the supporting means, a plurality of rearwardly extending uniformly spaced work holding members carried by the bar and normally arranged in substantially horizontal positions, the said work holding members having upturned hooked rear ends and pivoted latches arranged to swing between positions extending forwardly alongside the members and positions engaging with the hooked ends of the members, a plurality of uniformly spaced loop forming pins mounted for backward and forward adjustment on the supporting guide, the said pins having upwardly disposed forward ends arranged to extend rearwardly of and project upwardly between the rear end portions of the members when the pins are in forwardly adjusted positions, means for adjusting the pins forwardly and means for moving the pins rearwardly.

3. In a knitting machine, an elongated work holding member carrier, a plurality of uniformly spaced work holding members secured to the carrier and normally arranged in substantially horizontal parallel positions, the said members having upturned hooked rear ends and pivoted hook

closing latches, a plurality of parallel uniformly spaced loop forming pins mounted for backward and forward adjustment and having upstanding forward ends, the said pins being adjustable forwardly to positions whereby the upstanding forward ends extend upwardly between the rear end portions of the work holding members and forwardly of the hooked ends thereof, and the said pins being adjustable rearwardly to positions whereby their upturned portions are spaced rearwardly from the hooked ends of the work holding members, means for adjusting the pins forwardly, and separate means for adjusting the pins rearwardly.

4. In a knitting machine, an elongated carrier mounted for rotative adjustment, a plurality of uniformly spaced work holding members secured to the carrier and normally arranged in substantially horizontal parallel positions, the said members having upturned hooked rear ends and pivoted latches arranged to swing to and from forward positions alongside the members to rear positions engaging with the hooked rear ends of the members, a plurality of parallel uniformly spaced loop forming pins mounted for backward and forward adjustment, the said pins having upstanding loop forming forward ends and correspondingly positioned depending portions, the said pins being adjustable forwardly to positions whereby their upstanding forward ends extend upwardly between the rear end portions of the work holding members and forwardly of the hooked ends thereof, and the said pins being adjustable rearwardly to positions whereby their upstanding portions are spaced rearwardly from the hooked ends of the work holding members, a cam bar engageable with the depending portions of the pins for adjusting the said pins rearwardly, and separate means for adjusting the pins forwardly.

5. In a knitting machine, a plurality of uniformly spaced substantially parallel work holding members having upturned hooked rear ends and pivoted latch means arranged to open and close the said hooked ends, the said work holding members being normally arranged in substantially horizontal positions, and a plurality of uniformly spaced loop forming pins having upstanding end portions, the pins being adjustable forwardly to positions whereby their upstanding end portions extend between the rear end portions of the work holding members and forwardly of the hooked ends thereof, and the said pins being adjustable rearwardly to positions whereby their upstanding end portions are spaced rearwardly from the hooked ends of the work holding members.

6. In a knitting machine, a plurality of spaced work holding members mounted on a common adjustable support, the said members being normally arranged in horizontal and parallel positions, the said members having upturned hooked rear ends arranged in horizontal alignment and pivoted latches arranged to open and close the hooked ends, and a plurality of spaced loop forming pins having upstanding end portions, the pins being adjustable forwardly to positions whereby their upstanding end portions extend between the rear end portions of the work holding members and forwardly of the hooked ends thereof, and the said pins being adjustable rearwardly to positions whereby their upstanding end portions are spaced rearwardly from the hooked ends of the work holding members.

7. In a knitting machine, a plurality of uni-

formly spaced work holding members normally arranged in substantially horizontal positions and rigidly supported in parallel relation on a rigid elongated adjustable support, the said members having upturned hooked rear ends, pivoted latches mounted on the members and arranged to swing between forward positions closing the hooked ends of the members and open positions alongside the members, a plurality of uniformly spaced upstanding loop forming pins mounted for forward adjustment to strand engaging positions between the work holding members and the said pins being mounted for rearward adjustment to loop forming positions rearwardly of the work holding members, means for adjusting the pins forwardly, and separate means for adjusting the pins rearwardly.

8. In a knitting machine, an elongated frame, adjustable end supports mounted on the ends of the frame, an elongated bar mounted for partial turning on the end supports, a plurality of uniformly spaced work holding members rigidly secured to the bar and normally positioned in a substantially horizontal plane, the said members having upturned hooked rear ends, pivoted latches mounted on the members and arranged to swing between forward positions closing the hooked ends of the members and to open positions alongside the members, an elongated pin guide mounted on the frame having a plurality of uniformly spaced parallel transverse slots, a plurality of uniformly spaced loop forming pins adjustably mounted for forward and backward movement on the pin guide and having depending portions extending into the transverse slots and also having upstanding forward end portions, the said upstanding end portions being arranged to project upwardly between the forward end portions of the work holding members when in forwardly adjusted positions, and the said pins

being adapted to be rearwardly adjusted to positions whereby their upstanding portions are positioned rearwardly of the hooked rear ends of the work holding members, a cam bar engageable with the depending portions of the pins and the pin guide for shifting the pins rearwardly, and means for adjusting the pins forwardly.

9. In a knitting machine, an elongated substantially horizontal bar mounted for turning movement about a substantially horizontal axis, a plurality of uniformly spaced work holding members mounted on the bar and normally arranged in a common horizontal plane, the said work holding members having upturned hooked rear ends normally arranged in horizontal alignment and having also pivoted latches mounted for swinging movement between forward positions extending alongside the work holding members and rear positions engaging with the said hooked rear ends, a plurality of uniformly spaced upstanding loop forming pins mounted for forward adjustment to strand engaging positions between the work holding members, and the said pins being also mounted for rearward adjustment to loop forming positions located rearwardly of the hooked rear ends of the work holding members.
